(57) **CLAIM**

The ornamental design for a weightlifting implement, as shown and described.

DESCRIPTION

FIG. 1 is a top, front, right perspective view of a weightlifting implement showing our new design;

FIG. 2 is a bottom, rear, right perspective view thereof;

FIG. 3 is a right side view thereof;

FIG. 4 is a left side view thereof;

FIG. 5 is a rear view thereof;

FIG. 6 is a front view thereof;

FIG. 7 is a top view thereof; and,

FIG. 8 is a bottom view thereof.

The broken lines immediately adjacent to the shaded area define the bounds of the claimed design and form no part thereof. The broken lines depicting the remainder of the weightlifting implement show features that form no part of the claimed design.

1 Claim, 8 Drawing Sheets
